UNITED STATES PATENT OFFICE.

LOUIS McCARTHY, OF BOSTON, MASSACHUSETTS.

TROLLEY-WIRE INSULATOR.

SPECIFICATION forming part of Letters Patent No. 518,071, dated April 10, 1894.

Application filed June 8, 1893. Serial No. 477,015. (No model.)

To all whom it may concern:

Be it known that I, LOUIS McCARTHY, a citizen of the United States, residing at Boston, in the county of Suffolk and State of Massachusetts, have invented certain new and useful Improvements in Insulators, of which the following is a specification, reference being had therein to the accompanying drawings.

In the overhead construction of electric rail-
ways, an insulated hanger or support is em-
ployed which is placed between the span wire
and the trolley wire for the purpose of sus-
pending or supporting the latter in the well
known manner. An ear or clip is secured to
the trolley wire at the point where it is sup-
ported, and the insulator or hanger is usually
provided with a screw stud or downwardly
projecting bolt which screws into a socket in
the said ear or clip. It is important that the
insulator or hanger should be secured firmly
to the ear or clip and to this end it is impor-
tant to be able to screw the downwardly pro-
jecting bolt or connecting piece of the hanger
home in the socket of the ear. The insulated
hanger is provided with oppositely project-
ing arms or well known equivalent devices by
means of which it is made fast on the span
wire, and these arms are usually connected
by means of a screw bolt with the upper me-
tallic portions of the insulated hanger. The
hanger or insulator is therefore inserted be-
tween the arms by which it is made fast on
the span wire and the ear by which it is con-
nected with the trolley wire and is secured to
each of these parts, that is, to the arms and
to the ear by means of screw bolts. As the
line of the trolley wire is not always at ex-
actly the same angle with the span wire it fol-
lows that frequently the screws which secure
the insulated hanger in place and connect it
with the ear cannot be screwed home or if
screwed home have to be "backed off," as it
is termed, since if they are screwed home the
ear would not be in exact line with the trol-
ley wire as it must be for it is usually secured
thereto by solder, the trolley wire lying in the
groove lengthwise of the ear. To obviate
these objections and provide a trolley wire
hanger which may be firmly secured in place
and to the trolley wire or the ear thereon re-
gardless of the angle which the trolley wire

makes with the span wire is the chief object
of my present invention.

My invention further has for its object to
provide a strong and durable insulated hanger 55
which shall be capable of sustaining severe
lateral strain without breaking, and the outer
metallic case of which shall be of such shape
and relation to the insulator proper which is
contained within the same, as to fully protect 60
the insulator from any blow which it may re-
ceive from a misplaced trolley, and which
might operate to injure the insulator, all as
hereinafter more fully set forth.

In the accompanying drawings to which ref- 65
erence is made in the following description
my invention is shown in the best form now
known to me.

In said drawings Figure 1 is an elevation
partially in section of a trolley wire hanger 70
embodiment of my invention. Figs. 2 and 3 are
elevations of trolley wire hangers having re-
spectively double and single arms for connec-
tion with the span wire, the latter form shown
and Fig. 3 is more especially adapted for use 75
where the trolley wire is curved as in going
around a corner.

An insulator embodying my invention may
be described as consisting of two portions,
the outer bell-shaped case A provided with 80
an arm or arms B, said case serving as a holder
or support for the insulator proper and also
to protect the same fully, and the insulator
proper, which comprises a case adapted to be
received within the cavity of the outer bell- 85
shaped case, said inner case, or case of the
insulator proper, being covered, if desired,
with a layer of molded insulating composi-
tion, a connecting piece projecting within the
insulator, and a mass of insulating material 90
insulating the connecting piece from the in-
sulator case. As will be obvious the precise
construction of the insulator proper is not
material to my present invention, and various
well-known forms of insulators may be em- 95
ployed. I have shown what I consider to be
the preferred form of insulator, and to assist
in making the invention as shown in the ac-
companying drawings more clear, I will briefly
describe the same.

Referring to the drawings, Fig. 1 b is the
case of the insulator proper which is prefer-

ably bell-shaped as shown. *c* is a headed connecting piece placed therein; the outwardly or downwardly projecting end of the connecting piece being threaded so that it may be 5 screwed into the threaded socket in the ear or clip.

For the purpose of insulating fully the connecting piece *c* from the case *b*, I prefer to use a series of sheets of mica *f*; a cap or follower *d* is placed within the top of the case *b* after the connecting piece *c*, and the insulation have been placed therein, and the upper edges of the case *b* are by means of strong pressure, bent over the cap *d* solidifying the 15 insulation and securely fastening the parts together. An insulator thus constructed is shown in Letters Patent No. 491,729, dated February 14, 1893, granted to me, and a more detailed description of this portion of the de- 20 vice will not be necessary in the present instance, because such a description may be obtained upon reference to said patent, and also, because, as previously stated, the precise construction of the insulator proper is not es- 25 sential to my present invention, and any well known form of insulator may be employed.

At *h* I have shown a layer or covering of molded composition. This layer is molded over the said case, and upon the interior of 30 the skirt thereof as also around the projecting portion of the cap or follower *d*. While I prefer to use this exterior layer it will be obvious that it is not essential to my present invention and may be omitted if desired. 35 The arms *B* project in opposite directions from the bell-shaped receiver or outer case *A* and are preferably cast integral therewith, but the precise shape of said arms is not essential, any well known form of projection or device by means of which the span wire may be firmly secured to the insulator may be employed instead of the arms *B* which are shown. The top of the receiver or case *A* is preferably slightly thickened or pro- 40 vided with a boss as shown at *m* to strengthen it and is at this point provided with an aperture through which a screw bolt *h* is passed which screws into a threaded socket in the cap *d*. As will be clear if any insulator proper 45 of different internal construction from that shown be employed the bolt *h* will screw into the top or upper metallic portion of such insulator instead of into the cap *d*. As previously stated the downwardly projecting end 50 of the connecting piece *c* is threaded so that it may be screwed into the ear or clip which is soldered or otherwise secured to the trolley wire in the well known manner. By this construction the upper bolt *h* is not subject to 55 lateral strain but serves simply as a retaining point and to hold the insulator proper in the cavity in the receiver or bell *A*. Any lateral strain on the insulator is borne by the sides of the bell-shaped case *A*, being transmitted 60 to said case from the case *b* of the insulator proper. The danger therefore of the insulator being broken or separated from the arms or de- 65

vices by which it is secured to the span wire by lateral strain is reduced to a minimum. The receiver or bell-shaped outer case *A* is provided with a downwardly projecting skirt shown at *b'* which projects below any portion of the inner case of the insulator proper and serves not only as an extra watershed to keep moisture from the insulation, but also as a 70 protection in case a misplaced trolley is moved past the insulator. Without such protection the insulator may be subject to a blow from a trolley which might seriously impair it and in case an exterior molded covering like that 75 shown at *k* were employed such a blow might fracture this covering and thereby destroy or impair the value of the insulator. The downwardly projecting skirt *b'* is therefore of great value in preventing such accidental in- 80 jury.

In securing my improved insulator in place it is only necessary to screw the threaded connecting piece *c* home in the socket in the ear or clip, the top of the ear coming to a bearing on the under side of the insulator proper or on the metallic washer *l* which is firmly screwed or otherwise secured on the connecting piece *c*. When this is done (the hanger being properly secured on the span wire) if 90 the ear or clip is not in line with the trolley wire, it is only necessary to loosen the bolt *h*, turn the insulator proper in the outer bell or receiver *A* until the ear is in proper position with reference to the trolley wire, then screw 95 the bolt *h* firmly down. It will also be noted that if it becomes desirable for any purpose to remove the insulator it is only necessary to unscrew the bolt *h* which allows the insulator to be taken out of the receiver or outer 100 bell *A* and then to unscrew the insulator connecting piece *c* from the ear or clip. An insulator may thus be removed or another 105 one put in its place quickly and easily and without taking down any other parts of the 110 construction. It will be noted that the arms *B* are shown as of such shape that the body of the insulator and receiver *A* are substantially in line with the span wire, so that any lateral strain to which the insulator may 115 be subjected is borne in the most effective manner.

It will be obvious that the downwardly projecting skirt portion of the receiver *A* may be omitted and many of the advantages of 120 my improvement obtained. I do not therefore wish to limit myself to a receiver having a skirt or portion thereof projecting below the insulator proper.

What I claim is—

1. An insulator for trolley wires comprising an outer case or receiver having one or more arms by means of which the insulator may be secured to the span wire, an insulated portion fitting within said receiver, a screw bolt 130 passing through the top of the outer case or receiver and entering the upper part of such insulated portion for securing said insulated portion within said receiver and a screw con-

nection for securing said insulator to the ear or clip on the trolley wire, substantially as set forth.

2. An insulator for trolley wires comprising
5 an outer case or receiver having one or more arms by means of which the insulator may be secured to the span wire, an insulated portion fitting within said receiver, and a screw connecting piece for securing said insulator
10 to the ear or clip on the trolley wire, said receiver having a downwardly projecting skirt extending below the lower portion of the insulator proper which is within the receiver, for the purposes and substantially as set forth.
- 15 3. An insulator for trolley wires comprising an outer case or receiver provided with one or more arms by means of which the insulator may be secured to the span wire, an insulated portion fitting within said receiver,
20 said insulated portion having an exterior layer of insulating composition molded thereon, and screw connecting bolts for securing said insulated portion within the receiver as also for securing said insulated portion to the ear
25 or clip on the trolley wire, substantially as set forth.
4. An insulator for trolley wires comprising

an outer case or receiver having oppositely extending arms by means of which the insulator may be secured to the span wire, an insulated portion fitting within said receiver a screw connecting bolt passing through the top of the outer case or receiver and entering the top of the said insulated portion for securing said insulated portion within said receiver, and a second screw connecting-bolt 30 separate and independent from that aforesaid for securing said insulated portion to the ear or clip on the trolley wire, said oppositely extending arms being in line with the body 35 of the insulated portion when said portion is within the receiver whereby the span wire will be in line with the body of the insulated portion and below the securing bolt which secures said insulated portion within the receiver, substantially as and for the purposes 40 set forth.

In testimony whereof I affix my signature in presence of two witnesses.
